(22) Filed: **Jul. 31, 2003**

The ornamental design for an electric component placement machine, as shown and described.

(30) **Foreign Application Priority Data**

DESCRIPTION

Mar. 13, 2003 (JP) 2003-006583

FIG. 1 is a top perspective view of an electric component placement machine of the present invention;

(51) LOC (7) Cl. **15-99**

FIG. 2 is a front view thereof;

(52) U.S. Cl. **D15/199; D15/122**

FIG. 3 is a rear view thereof;

(58) Field of Search D15/122, 199;

FIG. 4 is a first side view thereof;

438/106; 29/833, 759, 836, 739-741, 832,
721

FIG. 5 is a second side view thereof;

(56) **References Cited**

FIG. 6 is a top view thereof;

U.S. PATENT DOCUMENTS

FIG. 7 is a bottom view thereof; and,

6,085,408 A * 7/2000 Watanabe 29/720

FIG. 8 is a top perspective view of a second embodiment of an electronic component placement machine of the present invention.

6,178,626 B1 * 1/2001 Hada et al. 29/833

The ornamental design which is claimed is shown in solid lines in the drawings. Any broken lines in the drawings are for illustrative purposes only and form no part of the claimed design.

6,240,628 B1 * 6/2001 Yoshida et al. 29/740

6,256,876 B1 * 7/2001 Ohe et al. 29/832

6,266,869 B1 * 7/2001 Tracy et al. 29/740

6,490,781 B2 * 12/2002 Kanai et al. 29/708

6,591,493 B1 * 7/2003 Yoshida et al. 29/832

UNITED STATES PATENT AND TRADEMARK OFFICE
CERTIFICATE OF CORRECTION

PATENT NO. : Des. 493,808 S
DATED : August 3, 2004
INVENTOR(S) : Yasuhiko Tanaka et al.

Page 1 of 1

It is certified that error appears in the above-identified patent and that said Letters Patent is hereby corrected as shown below:

Title page.

Item [75], Inventors, delete "Yosuhiko" and substitute -- **Yasuhiko** -- in its place.

Signed and Sealed this

Fifteenth Day of February, 2005

JON W. DUDAS
Director of the United States Patent and Trademark Office
